UNITED STATES PATENT OFFICE.

CHARLES F. PYM, OF LYNN, MASSACHUSETTS, ASSIGNOR TO UNITED SHOE MACHINERY CORPORATION, OF PATERSON, NEW JERSEY, A CORPORATION OF NEW JERSEY.

MACHINE FOR USE IN LASTING BOOTS AND SHOES.

Application filed May 10, 1919, Serial No. 296,213. Renewed October 9, 1922. Serial No. 593,442.

To all whom it may concern:

Be it known that I, CHARLES F. PYM, a subject of the King of England, residing at Lynn, in the county of Essex and State of Massachusetts, have invented certain Improvements in Machines for Use in Lasting Boots and Shoes, of which the following description, in connection with the accompanying drawings, is a specification, like reference characters on the drawings indicating like parts in the several figures.

This invention relates to machines for use in the manufacture of boots and shoes, and more particularly to machines for use in that part of shoe manufacture in which the upper is conformed to the contour of the last, for example round the end portion of the shoe.

A feature of the invention consists in novel means for applying a binder round the end of a shoe to hold the upper in conformity to the contour of the last. As explained in my earlier Patent No. 1,412,892, granted on April 18, 1922, advantages are involved for some purposes in shoe manufacture in the use of a lasting binder applied round the end of a shoe exteriorly of the periphery of the shoe bottom, i. e. round the end face of the shoe, and the construction herein shown is designed to apply a binder in this location, although the invention is not thus limited in its applicability. To this end the illustrative machine has means for engaging a binder, such for example as a band of flexible material, substantially continuously round the end of the shoe and for forcing the different portions of the binder against the upper with substantially uniform pressure and for holding the binder in position to be fastened to the shoe.

A further feature of the invention consists in a novel construction and arrangement of means for applying a binder in holding relation to an upper round the end of a shoe and for fastening the binder in holding position. The construction herein shown is particularly designed for applying to a shoe a binder having laterally projecting flange portions adapted for use in fastening the binder to the shoe, and to this end comprises means for driving fasteners such as tacks through the flange portions of the binder to fasten the binder to the shoe. It will be understood, however, that in its broader aspects the invention is not limited to the

specific means illustrated for fastening the binder.

The invention is herein illustrated as embodied in a machine having means for pulling the upper into conformity to the contour of the last and means for wiping the margin of the upper inwardly round the end of the shoe over the margin of the sole or insole (hereinafter frequently termed generically the "sole"). The wiping means thus provided serves to gather the upper materials along the edge of the shoe bottom in preparation for the application of the binder round the lateral periphery of the shoe and also, by bending and wiping the margin of the upper inwardly, assists in forming a sharply defined edge line along the periphery of the sole or insole and applies to the margin a preliminary forming or molding pressure such as to facilitate the subsequent operation whereby the upper is permanently secured to the sole or insole. Further important features of the invention are to be recognized in the combination thus provided of means for conforming the upper to the contour of the last and means for securing it by the use of a binder, although it will be understood that in its broader aspects the invention is not limited to a construction including upper pulling means and overlaying means.

The above and other features of the invention, including also novel means for subjecting the margin of an upper to overlaying and molding pressure, and certain details of construction and combinations of parts will now be described with reference to the accompanying drawings and pointed out in the claims.

In the drawings:

Figure 1 is a view partly in side elevation and partly in vertical section of a portion of a pulling-over and toe lasting machine in which the invention is embodied;

Fig. 2 is a view looking down on the shoe and the wipers with parts in section in a plane at an angle to the horizontal illustrating more fully than Fig. 1 the relation of the shoe to the upper pulling, overlaying and binder applying and fastening means;

Fig. 3 is a view similar to Fig. 2 of a portion of the mechanism there shown, illustrating the relation of the mechanism to the shoe at a later stage in the cycle of operations;

Fig. 4 is a sectional view illustrating in

greater detail the operation of the machine upon an end portion of the binder;

Fig. 5 is a view with parts in section in a plane parallel to that of Fig. 2 showing 5 mechanism with which the machine is provided for operating the overlaying and binder applying and fastening means;

Fig. 6 is an end view of the overlaying wipers and the means for applying the 10 binder round the end of the shoe;

Fig. 7 is a section on the line 7—7 of Fig. 2 on an enlarged scale, and

Fig. 8 shows the toe portion of a shoe as it 15 appears after having been operated upon by the machine.

The invention is herein illustrated as embodied in mechanism designed to form a part of a well-known type of pulling-over machine characteristic features of which are 20 shown and described in detail in prior United States Letters Patent No. 1,029,387, granted on June 11, 1912, upon an application of R. F. McFeely, the machine herein shown embodying also certain features relating particularly to the toe lasting means 25 which are more fully shown and described in Letters Patent No. 1,436,194 granted upon my application on Nov. 21, 1922. Only such portions of the machine as have 30 particularly to do with the novel features of this invention are shown herein in detail, and for a more complete understanding of the organization and mode of operation of the machine as a whole reference may be 35 made to said prior patents.

The machine is provided with means for gripping and pulling the upper at the toe end and at opposite sides of the forepart of the last, comprising toe gripper jaws 2 and side 40 gripper jaws 4, the toe gripper jaws being operated through a bar 6 by an updraw lever 8 to grip and pull the upper, and the side gripper jaws being similarly operated by means not shown herein in detail. To 45 position the shoe for the upper pulling operation the machine is provided with a sole rest 10 which holds the last against strain as the upper is pulled and is also rocked downwardly by means of a cam 12 in time 50 relation to the operation of the grippers to assist in stretching and conforming the upper to the contour of the last. At the time of the upper pulling operation, also, a heel rest 14 is moved up into supporting relation 55 to the heel end of the shoe to resist backward thrust in subsequent operations on the shoe. The illustrative machine is further provided with additional work positioning means comprising a member 16 for embracing 60 the toe end of the last to determine its initial lengthwise position and a member 18 for engaging the margin of the sole or insole adjacent to its edge to hold it in the correct 65 relation to the surface of the last bottom. The members 16 and 18 are subsequently

withdrawn from operative position by means fully described in my prior patent and which it is not necessary to describe herein in detail. It is to be understood, moreover, that as far as the features of the present invention are concerned, one or both of these members may be omitted in case the character of the work is such as to render their use unnecessary.

It will be understood that in the operation of machines of the illustrative type the machine comes to rest immediately after the upper pulling operation to permit inspection of the work and such adjustment as may be necessary in order to insure the proper tensioning of the different portions of the upper and the proper relation of the lines of the upper to the contour of the last. Upon a subsequent starting of the machine, shoe clamping and supporting mechanism is moved into holding and supporting relation to the forepart of the shoe, such mechanism comprising pads 20 which engage the shoe at opposite sides and additional pads 22 which underlie the forepart of the shoe 90 to support it against the subsequent operation of the overlaying and fastening means. Following the movement of this clamping and supporting mechanism to operative position, the side grippers are rendered operative to draw the margin of the upper inward over the sole or insole, these grippers being followed in their inward movement by side overlaying and fastening mechanisms which finally cause the grippers to release 95 the margin of the upper and are then operated to fasten the upper in overlaid position at the sides. These mechanisms comprise side arms 24, shown in section in Fig. 5, upon which are mounted overlaying wiper plates 26 and 28, tack holders 30 and 32 and tack drivers 34. These side wiper plates may be mounted and controlled, for example, as shown in a prior Patent No. 1,409,190, granted on March 14, 1922, on an application of R. F. McFeely and owned by the assignee of the present application. The inward movement of the side arms 24 is accompanied by rearward movement of a front arm 36 which is pivoted on a bracket 38 and supports at its lower end a pair of end embracing wipers 40 and means underneath said wipers for positioning a binder and applying it to the shoe, the wipers and the binder applying means being mounted in a holder 42 which, similarly to the wiper mechanism of my earlier patent, is pivoted at 44 on the arm 36 for adjustment relatively to the plane of the shoe bottom as well as for yielding movement against the tension of a spring 46 in response to abnormal resistance of the shoe materials.

The wipers 40, as in the construction shown in my prior patent, are connected together by a pivot 48 and are detachably se- 130

cured by means of pins 50 to gear segments 52. These segments are mounted in grooves in the holder 42 for swinging movement about the axis of the pivot 48 and are engaged by pinions 54 which are connected to rack bars 56 mounted to slide in guideways in the holder 42 and normally positioned with their inner ends against limiting stops 58. Pivotedly mounted on the frame of the machine are wiper controlling arms 60 which are forked at their lower ends to embrace the respective rack bars 56 and carry adjustable stop screws 62 arranged to engage fixed lugs 64 at a predetermined time in the operative movement of the arm 36. Encircling each of the rack bars 56 between a bearing washer 66 and an adjustable tension nut 68 is a spring 70. Springs 72 connected at their opposite ends respectively to the holder 42 and to the lower ends of the arms 60 tend to pull the arms toward the holder and through washers 74 which engage shoulders on the rack bars 56 to hold these bars normally at their inner limit of movement. It will be understood that upon movement of the arm 36 rearwardly toward the shoe the ends of the stop screws 62 are carried into engagement with the lugs 64, whereupon movement of the arms 60 in that direction is stopped and through the springs 70 the rack bars 56 are held substantially stationary, thus causing the pinions 50 in the continued movement of the arm 36 and the holder 42 to operate the gear segments 52 and swing the wipers inward laterally of the shoe. In case one or both of the wipers 40 encounter abnormal resistance to inward movement prior to the completion of the movement of the wiper mechanism as a whole lengthwise of the shoe, the construction affords provision for yield of the corresponding spring or springs 70, thus permitting said wiper or wipers to continue the movement lengthwise of the shoe without further closing movement laterally of the shoe. In the return of the parts to starting position the springs 72 cause the arms 60 and the bracket 42 to approach each other, whereby the rack bars are moved inward in their guideways and the gear segments are operated to open the wipers to their initial position.

At a predetermined time in the movement of the wiper mechanism lengthwise of the shoe the toe gripper is tripped to cause it to release the margin of the upper, such tripping of the gripper preferably taking place substantially at the time when the edges of the wipers arrive in position to engage the margin of the upper and wipe it inward. The tripping of the toe gripper is effected by means of a latch 76 connected by a bar 78 to a finger 80 which is arranged to be operated by a member 82 secured to the arm 36. The toe gripper is under the control of a spring 84

which tends to move it forwardly as permitted by rolls 86 in engagement with the inclined faces of projections 88 on the gripper casing, the gripper thus being pulled forward yieldingly by the spring 84 during its updraw movement. The spring 84 is connected to a pivot bar 90 which carries a screw 92 in engagement with the front face of the arm 36, and thus the rearward swing movement of the arm 36 serves to relieve the tension of the spring 84 and permit the toe gripper to swing more or less rearwardly in response to the pull of the upper as well as in response to such pressure as may be applied to it through the latch 76 in the continued rearward movement of the arm 36 after the gripper is tripped.

Secured on the lower side of the wipers 40, for the purposes of this invention, are binder applying plates 94 having their front edge faces curved in substantial conformity to the curve of the corresponding portions of the lateral periphery of the shoe. These plates have a thickness substantially equal to the width of a binder *a* comprising a band of thin flexible material such as sheet metal adapted to be applied round the end face of the shoe. Mounted pivotally on studs 96 which are fastened to the wipers are binder supporting plates 98, these plates being arranged to project beyond the front edge faces of the members 94 in position to support the binder and yieldingly held in such position against stop pins 100 by means of springs 102 which permit the plates to be swung backward upon engagement with the shoe. Additional supporting means for the intermediate portion of the binder is afforded by a member 104 mounted to slide in a guideway in the holder 42 and normally held by means of a spring 106 with its front end portion projecting forwardly beyond the edge faces of the plates 94, this member being yieldable backwardly against the tension of its spring upon engagement with the end face of the shoe. In order further to insure that the binder shall be held in place, the member 104 is provided with a pivoted spring controlled catch 108 the upper edge of which is suitably rounded to permit the binder to slip by it readily both when the binder is placed in position and when the supporting member is stopped by engagement with the shoe. It will be evident that with the mechanism thus provided the binder *a* is carried into engagement with the shoe as the wipers are operated and is pressed firmly by the members 94 against the upper materials round the lateral periphery of the toe end of the shoe.

The binder herein shown is provided at its opposite ends with laterally projecting flanges *b* which are adapted to overlie portions of the upper materials on the margin of the shoe bottom to assist in fastening the

binder to the shoe. Preferably the binder is so formed that the flanges *b* project initially, as shown, in an inclined relation to the plane of the adjacent body portion of the binder, thus permitting the binder to be applied readily to the shoe without danger that the flanges may catch objectionably in the margin of the upper. The machine is designed to bend the flanges *b* down upon the margin of the shoe bottom and to fasten the binder to the shoe by driving tacks through these flanges. For this purpose the foremost wiper plate 26 and its associated tacking mechanism at each side of the machine are utilized. By reference to Fig. 4 it will be seen that the wiper plate 26 has an upturned end portion, and also a downturned flange portion 110 located at the inner edge of the slot in the wiper through which the tacks are driven. As the side wipers approach the shoe the plates 26 are carried into engagement with the upturned flanges *b* of the binder and in their continued movement serve to bend the flanges down over the margin of the shoe bottom, the downturned projections 110 being carried into engagement with the portions of the binder adjacent to said flanges and thus assisting in the bending operation as well as in pressing the end portions of the binder closely against the lateral periphery of the shoe. It will be understood that the wiper plates 26 are permitted to yield backward relatively to their supporting arms, as usual in machines of the illustrative type, thus permitting the arms to complete their operative movement toward the shoe in order to carry the tacking mechanisms into the correct relation to the edge of the shoe bottom. The arms having arrived at their inner limit of movement, the tack drivers 34 are operated in the well-known manner to drive the several tacks, the two foremost tacks on each side being driven through the downturned flange *b* of the binder, as illustrated in Figs. 3 and 8, to fasten the binder securely to the shoe. As shown in Fig. 8, the binder securing tacks are only partially driven, thus permitting the binder to be readily detached from the shoe when required.

The means for imparting operative movement to the side arms 24 and to the front arm 36 and for returning them subsequently to their starting positions is shown in Fig. 5. This mechanism comprises a rack bar 112 engaged and operated by a pinion 114 and carrying at its front end spring plungers 116 which engage inclined faces on plates 118 mounted to slide in guideways in the sides of the front arm 36. The rack bar 112 at its opposite sides is connected to pivoted gear segments 120 connected in turn to slides 122 which carry spring plungers 124 in engagement with inclined faces on plates 126 connected to the side arms 24. Rearward

movement of the bar 112 thus serves to swing the arm 36 and its supported wipers and binder applying means rearwardly toward the shoe and also to swing the side arms 24 and their supported wiping and tacking mechanisms inwardly toward the opposite sides of the shoe. In the present construction the front arm 36 and its supported wipers and binder applying means are positioned comparatively close to the toe end of the shoe in order to insure that the flanged ends of the binder *a* shall be carried rearwardly and inwardly toward the shoe in such manner as to be engaged by the wiper plates 26 before these plates are carried into engagement with the shoe materials. It is contemplated that in this construction resistance to the movement of the arm 36 lengthwise of the shoe by reason of pressure of the binder applying members 94 against the lateral periphery of the shoe may be encountered before the side arms 24 have completed their inward movement, and with this in view the plates 118 are extended rearwardly to provide slideways of considerable length along which the plungers 116 may move in the continued rearward movement of the rack bar 112 after the operative movement of the arm 36 has been stopped. The side wipers and tackers are thus permitted to complete their operative movement, the tack drivers being finally actuated through relative movement between the slides 122 and 126 against the resistance of the spring plungers 124, as usual in machines of the type illustrated.

The machine is also provided with novel mechanism for operating the wipers 40 in such manner as to press the margin of the upper down on the sole or insole in the over-wiping operation. To this end the front arm 36 is mounted on an eccentric 128 which is arranged normally as shown in Fig. 1 and is turned, during the operative movement of the wipers, in a direction to impart lengthwise downward movement to the arm 36. The connections for operating the eccentric 128 comprise a crank arm 130 pivotally connected to a link 132 extending through a sleeve 134 pivotally mounted on the outer end of one arm of a bell crank 136, the other arm of the bell crank being connected by a link 138 to the arm 36. A stop collar 140 adjustably secured on the link 132 in position to be engaged by the sleeve 134 causes the eccentric 128 to be positioned by the arm 36 normally as shown by means of the connections 136 and 138. When operative movement is imparted to the arm 36 to carry the wipers toward the shoe the bell crank 136 is operated by the link 138 to carry the sleeve 134 into engagement with a washer 142 which is slidable on the link 132 against the resistance of a spring 144, and in the continued movement of the arm 36 the crank 130

arm 130 is operated yieldingly through the spring 144 to turn the eccentric 128 in a direction to depress the arm 36 and its supported wiper mechanism. As shown in Fig. 5 1, there is provision for lost motion between the sleeve 134 and the washer 142, the purpose of this arrangement being to permit the wipers to advance substantially into position to operate on the shoe before their 10 downward pressing movement begins, such movement being imparted to the wipers during their entire inward wiping movement over the shoe to compress the margin of the upper progressively as it is overwiped. 15 When the arm 36 is returned to its starting position the sleeve 134 in engagement with the stop collar 140 serves to return the eccentric to its initial position.

In order to guard against interference between the mechanism carried by the front arm 36 and other portions of the machine in case the machine is operated in the absence of any shoe, the arm 36 carries a bar 146 mounted to slide loosely through a lug 148 25 on the frame of the machine and carrying a nut 150 for engagement with said lug to limit rearward movement of the arm 36 and the wiper mechanism. Such limiting means is of particular utility in the machine illustrated for the reason that the arm 36 and the wiper mechanism, as hereinbefore explained, are positioned initially in a comparatively close relation to the end of the shoe and in the idle operation of the machine would, if 30 35 limiting means were not provided, be carried farther rearwardly than is usual in machines of this type, with the possibility of damaging portions of the machine.

In the use of the machine, a binder *a* 40 formed with end flanges *b* as hereinbefore described is positioned between the wipers 40 and the underlying supports 98 and 104, as indicated in Fig. 1, the intermediate portion of the binder being slipped past the spring catch 108 which then assists in retaining it in position. It will be understood 45 that the binder as prepared for use in the machine may be curved approximately in shoe form or may be substantially straight, and that the end flanges may or may not be 50 partially bent inward as indicated in Fig. 2 and by broken lines in Fig. 4. In using a straight binder the operator will bend it as he places it in position between the wipers 55 and the binder supports.

The binder having thus been positioned for use upon a shoe, a last with shoe materials assembled thereon is presented by the operator in the position indicated in Fig. 1 with the sole or insole engaging the shoe rest 10 and the end of the last substantially in engagement with the member 16 to position it lengthwise, the margin of the upper materials being arranged within the open jaws of the toe and side grippers. The

machine is then started and the upper is pulled in the usual manner and is then held under tension with the machine at rest to permit inspection of the work and any necessary adjustment. When the machine is again 70 started the shoe clamping and supporting devices 20 and 22 are moved into operative position, and the upper is overdrawn, wiped inward and fastened by tacks at the opposite sides of the shoe in the manner hereinbefore described. Simultaneously with the operative movement of the side arms 24 which carry the side wiping and tacking mechanisms, the front arm 36 is operated to cause the wipers 40 to wipe the margin of 80 the upper inward round the toe end of the shoe and to compress the margin on the shoe bottom through the operation of the eccentric 128. As the wipers arrive at their limit of lengthwise and inward closing movement, 85 the binder is pressed firmly against the upper round the entire lateral periphery of the toe end of the shoe to hold this portion of the upper conformed to the last in the manner substantially determined by the upper pulling operation and the gathering and overwiping action of the wipers. As hereinbefore explained, the operation of the arm 36 is suitably timed to cause the flanged end portions of the binder to be carried rearwardly and inwardly toward the sides of 90 the shoe in such manner that the fastening flanges *b* are engaged by the incoming wipers 26. These wipers serve by means of their projections 110 to press the end portions of the binder against the lateral periphery of the shoe and serve also to bend down the flanges *b* upon the inwardly extending margin of the upper, whether or not 95 these flanges have been partially bent, as indicated, in the preparation of the binder. The inward movement of the side wiping and tacking mechanisms is completed after the front arm 36 has completed its rearward movement, and the tacks are then driven at 100 the sides as hereinbefore explained, the inwardly bent flanges *b* being positioned to receive the two foremost tacks on each side, as shown in Fig. 3. The parts of the machine are then returned to starting position 105 and the shoe is released.

The invention is herein illustrated by reference to its use upon a shoe of the McKay type, and in such use the shoe is prepared for a subsequent operation whereby the upper is 110 permanently secured to the insole, as explained, for example, in my earlier Patent No. 1,412,892. In the use of the invention in the manufacture of shoes of other types, for example welt shoes and turn shoes, it is 115 contemplated that the shoe with its toe portion held by the binder round its end face may be presented to the sewing machine for permanently securing the upper to the sole or insole without further preparation in the 120 125 130

way of lasting round the toe. In the operation of the machine upon welt or turn shoes, the wipers will serve to crease the upper preliminarily into the angle between the feather and the shoulder or rib of the sole or insole, as well as to cooperate with the binder in forming a sharply defined edge along the margin of the shoe bottom, and thus will assist the operation of the sewing machine in pressing and drawing the margin of the upper tightly into its required position. In use on McKay work also the wipers co-operate with the binder and the binder applying means to form a sharply defined edge line on the upper along the margin of the insole, and by their wiping and pressing action serve to mold the inturned flange preliminarily and thus to permit the subsequent upper and sole connecting operation to be performed readily without the necessity for any particular skill upon the part of the operator.

Having described the invention, what I claim as new and desire to secure by Letters 25 Patent of the United States is:

1. A machine of the class described having, in combination, means for conforming an upper to the contour of a last, and means for applying a binder round the end of 30 the shoe exteriorly of the periphery of the shoe bottom and for fastening the binder to the shoe.

2. A machine of the class described having, in combination, means for conforming 35 an upper to the contour of a last, and means for applying a binder round the end face of the shoe and for fastening the binder to a portion of the shoe materials on the bottom of the last.

40 3. A machine of the class described having, in combination, means for conforming an upper to the contour of a last, and means for applying a binder round the end of the shoe exteriorly of the periphery of the 45 shoe bottom and for bending a portion of the binder inwardly over the shoe bottom and fastening it to the shoe.

4. A machine of the class described having, in combination, means for conforming 50 an upper to the contour of a last, means for applying round the end face of the shoe an upper holding band having laterally extending attaching flanges, and means for fastening said flanges to the shoe.

55 5. A machine of the class described having, in combination, means for conforming an upper to the contour of a last, means for applying round the end face of the shoe an upper holding band having a portion 60 adapted to extend inwardly over the shoe materials on the bottom of the last, and means for driving a fastener to secure said inwardly extending portion of the band to the shoe materials.

65 6. A machine of the class described hav-

ing, in combination, means for conforming an upper to the contour of a last, means for applying a binder round the end of the shoe exteriorly of the periphery of the shoe bottom, and means for driving fasteners through said binder to fasten it to the shoe. 70

7. A machine of the class described having, in combination, means for conforming an upper to the contour of a last, means for applying round the end of the shoe an upper holding binder having laterally projecting attaching flanges, and means movable relatively to the binder to drive fasteners through said flanges to fasten the binder to the shoe. 75

8. A machine of the class described having, in combination, means for conforming an upper to the contour of a last, means for applying round the end face of the shoe a binder having on its end portions laterally extending flanges adapted to overlie portions of the shoe materials on the bottom of the last, and means for driving fasteners through said flanges to fasten the binder to the shoe. 80

9. A machine of the class described having, in combination, means for conforming an upper to the contour of a last, means for applying round the end face of the shoe a binder having laterally extending attaching flanges, and means for bending said flanges over the materials on the bottom of the last and for driving fasteners through said flanges to fasten the binder to the shoe. 85

10. A machine of the class described having, in combination, means for conforming an upper to the contour of a last, means for applying round the end face of the shoe an upper holding band, and means for bending a portion of said band over the shoe 105 materials on the bottom of the last and for driving a fastener to secure it to said materials.

11. A machine of the class described having, in combination, means for pulling an upper over a last, and means for applying an upper holding binder round the end face of the shoe and for fastening the end portions of said binder to the shoe. 110

12. A machine of the class described having, in combination, means for pulling an upper over a last, means for applying a binder round the end face of the shoe in position to clamp the upper against the edge face of the sole, and means for fastening the binder to the shoe. 115

13. A machine of the class described having, in combination, means for pulling an upper over a last, means for applying round the end face of the shoe a binder having on its ends attaching portions adapted to overlie the shoe materials on the bottom of the last, means for wiping the margin of the upper inwardly at the sides of the shoe, and means for fastening said attaching por- 120

tions of the binder to the overwiped margin of the upper.

14. A machine of the class described having, in combination, means for pulling an upper over a last, means for overlaying and fastening portions of the upper at opposite sides of the shoe, and means for applying a binder round the end face of the shoe and for presenting the end portions of the binder in position to be fastened on the bottom of the shoe by said upper fastening means.

15. A machine of the class described having, in combination, means for pulling an upper over a last, means for overlaying and fastening portions of the margin of the upper at the opposite sides of the shoe, and means for applying round the end face of the shoe a binder having on its end portions laterally projecting attaching flanges and for positioning said flanges in operative relation to said overlaying and fastening means to cause them to be bent inward over the shoe bottom and fastened to the shoe by said means.

25 16. A machine of the class described having, in combination, means for pulling an upper over a last, means for applying a binder around the end face of the shoe, overlaying means comprising side wipers, means 30 on said wipers for engaging the end portions of the binder and pressing them against the lateral periphery of the shoe, and means for fastening the binder to the shoe.

17. A machine of the class described having, in combination, means for working an upper over a last, side tackers movable inwardly over the margin of the shoe bottom at opposite sides of the shoe, and means for applying round the end face of the shoe a binder having attaching portions adapted to overlie the shoe materials on the bottom of the last and for presenting said attaching portions in position to receive tacks driven by said side tackers.

45 18. A machine of the class described having, in combination, shoe positioning means, end embracing wipers, means for operating said wipers, and means carried by said wipers for applying an upper holding binder round the end face of the shoe.

19. A machine of the class described having, in combination, shoe positioning means, end embracing wipers, and binder applying members carried by said wipers, said members having faces curved in substantial conformity to the lengthwise curvature of the edge of the shoe bottom and arranged to press an upper holding binder into engagement with the shoe exteriorly of the periphery of the shoe bottom.

20. A machine of the class described having, in combination, shoe positioning means, and embracing wipers, binder applying members secured to said wipers and arranged to apply a binder round the end face of the

shoe, and means for supporting a binder in operative relation to said members.

21. A machine of the class described having, in combination, shoe positioning means, end embracing wipers, means carried by said 70 wipers for engaging a binder and pressing it against the lateral periphery of the shoe, and members constructed and arranged to support a binder in operative relation to said binder engaging means and to yield upon 75 contact with the shoe to permit the binder to be applied to the shoe.

22. A machine of the class described having, in combination, shoe positioning means, end embracing wipers, means carried by said 80 wipers for applying a binder round the end face of the shoe and for holding the binder pressed against the shoe, and means for fastening the binder to the shoe while it is thus held.

23. A machine of the class described having, in combination, shoe positioning means, end embracing wipers, means for operating said wipers, means for positioning adjacent to said wipers a binder having flanged end 90 portions projecting rearwardly beyond the wipers, means for applying said binder round the end face of the shoe, and means for fastening said flanged end portions of the binder to the shoe.

24. A machine of the class described having, in combination, shoe positioning means, end embracing wipers, means for operating said wipers, means for positioning adjacent to said wipers a band of flexible binder material having end portions projecting rearwardly beyond the wipers, means for applying the binder round the end of the shoe, and means for bending parts of said rearwardly projecting portions of the binder 100 over the shoe bottom and for driving fasteners through said parts.

25. A machine of the class described having, in combination, means for pulling an upper over a last, end embracing wipers, 110 means for operating said wipers, means for fastening the upper at the sides of the shoe, and means for applying round the end face of the shoe an upper holding binder having end portions adapted to be fastened to the 115 shoe and for presenting said end portions of the binder in position to be fastened to the shoe by said upper fastening means.

26. A machine of the class described having, in combination, means for pulling an 120 upper over a last, end embracing wipers, means for operating said wipers, side wiping and tacking mechanisms, and means for applying round the end face of the shoe a binder having laterally projecting flange 125 portions and for presenting said flange portions of the binder in position to be bent over the bottom of the last and fastened to the shoe by the side wiping and tacking mechanisms.

27. In a machine of the class described, the combination with shoe positioning means, of means for applying a lasting binder round the end of the shoe exteriorly of the periphery of the shoe bottom and for fastening said binder to the shoe.
28. In a machine of the class described, the combination with shoe positioning means, of means for applying a band of flexible binder material round the end face of the shoe, and means for bending portions of said band inwardly over the shoe bottom and fastening them to the shoe.
29. In a machine of the class described, the combination with last and upper positioning means, of means for applying round the end face of the shoe an upper holding binder comprising a band of flexible material provided at its ends with flanges adapted to overlie portions of the margin of the upper on the bottom of the last, and means for driving fasteners through said flanges to fasten the binder to the shoe.
30. In a machine of the class described, the combination with shoe positioning means, of binder applying means comprising members having front faces curved in substantial conformity to the lengthwise curvature of the edge of the shoe bottom and arranged to press a binder into holding relation to the upper of the shoe round the end of the shoe exteriorly of the periphery of the shoe bottom.
31. In a machine of the class described, the combination with shoe positioning means, of binder applying means comprising a pair of members pivoted to swing about an axis substantially at the end of the shoe and having their front faces curved in substantial conformity to the curve of the corresponding portions of the edge of the shoe bottom, said members being arranged to press a binder into holding relation to the upper round the end face of the shoe, and means for supporting a binder in operative relation to said members.
32. In a machine of the class described, the combination with shoe positioning means, of means for applying an upper holding binder round the end of the shoe exteriorly of the periphery of the shoe bottom, said binder applying means being constructed and arranged to hold the binder by pressure directed laterally against substantially all portions of it simultaneously, and means for fastening the binder to the shoe while it is thus held.
33. In a machine of the class described, the combination with shoe positioning means, of means for applying a binder round the end face of the shoe, additional means for engaging the end portions of the binder and pressing them against the lateral periphery of the shoe, and means for fastening the binder to the shoe.
34. In a machine of the class described, the combination with shoe positioning means, of means for applying round the end face of the shoe a binder having flange portions adapted to be bent inwardly over the shoe bottom, and side wipers arranged to bend said flange portions of the binder inwardly, said wipers having means arranged to engage the binder adjacent to said flange portions and press the binder against the lateral periphery of the shoe.
35. In a machine of the class described, the combination with last and upper positioning means, of a wiper for wiping the margin of the upper over the bottom of the last, supporting means movable to carry the wiper inwardly over the bottom of the last, and additional means arranged to be operated by the inward movement of the wiper for moving the wiper in a different direction to cause it to compress the margin of the upper.
36. In a machine of the class described, the combination with last and upper positioning means, of a wiper for wiping the margin of the upper inwardly over the bottom of the last, a wiper support, an eccentric member on which said support is mounted, means for imparting operative movement to said support, and connections between said support and eccentric member for turning said member in a direction to cause the wiper to compress the margin of the upper during its overwiping movement.
37. In a machine of the class described, the combination with last and upper positioning means, of end embracing wipers, a wiper support movable to carry the wipers lengthwise of the shoe for wiping the margin of the upper inwardly, an eccentric upon which said support is mounted, and means arranged to be operated by movement of said support toward the shoe for turning said eccentric in a direction to cause the wipers to compress the margin of the upper.
38. In a machine of the class described, the combination with last and upper positioning means, of end embracing wipers, a wiper support movable to carry the wipers lengthwise of the shoe for wiping the margin of the upper inwardly, an eccentric upon which said support is mounted, and yielding connections between said support and eccentric for turning said eccentric in a direction to cause the wipers to compress the margin of the upper yieldingly during their overwiping movement.
39. In a machine of the class described, the combination with last and upper positioning means, of end embracing wipers, means for operating said wipers to wipe the margin of the upper inwardly over the bottom of the last, means for embracing the upper round the end of the last close to the edge of the last bottom to conform the upper to

the contour of the lateral periphery of the last, and means for imparting to said wipers substantially throughout their inward movement over the shoe a component of movement in a direction transverse to the plane of the last bottom to compress the margin of the upper and in co-operation with said end embracing means to form a sharply defined edge line on the upper.

40. In a machine of the class described, the combination with last and upper positioning means, of an overlaying member mounted for movement inwardly over the bottom of the last, a device for forcing said member toward the plane of the last bottom, and lever connections between said device and member for operating the device by the inward movement of the member.

41. In a machine of the class described, the combination with last and upper positioning means, of a wiper for wiping the margin of the upper inwardly over the bottom of the last, a wiper support movable to operate said wiper, a member movable in wedging engagement with said wiper support to force the wiper toward the plane of the last bottom, and connections arranged to be operated by movement of the wiper support for imparting operative movement to said wedging member.

42. In a machine of the class described, the combination with last and upper positioning means, of a wiper for wiping the margin of the upper inwardly over the bottom of the last, a wiper support movable to operate said wiper, an eccentric member on which said support is mounted, and a bell-crank having its arm connected respectively to said eccentric member and to said wiper support for turning said member in a direction to force the wiper in its overwiping movement toward the plane of the last bottom.

43. In a machine of the class described, the combination with means for pulling an upper over a last, of toe embracing wipers mounted for movement inwardly over the shoe, and mechanism automatically operative substantially throughout the overwiping movement of said wipers over the shoe to force them toward the plane of the shoe bottom for applying progressively increasing pressure to the margin of the upper.

44. In a machine of the class described, the combination with means for pulling an upper over a last, of toe embracing wipers, a wiper support mounted for movement lengthwise of the shoe to operate said wipers, and mechanism arranged to be operated by said movement of the wiper support for forcing the wipers progressively toward the plane of the shoe bottom in their overwiping movement.

45. In a machine of the class described, the combination with means for pulling an

upper over a last, of a front arm mounted for swinging movement lengthwise of the shoe, end embracing wipers carried by said arm, and mechanism arranged to be operated by the swinging movement of said arm to move the arm and the wipers in a direction transverse to the plane of the shoe bottom for compressing the margin of the upper.

46. In a machine of the class described, the combination with means for pulling an upper over a last, of a front arm mounted for swinging movement lengthwise of the shoe, end embracing wipers carried by said arm, an eccentric member forming a pivotal support for said arm, and connections arranged to be operated by swinging movement of said arm for turning said eccentric member to impart to the wipers a compressing movement toward the plane of the shoe bottom.

47. In a machine of the class described, the combination with means for conforming an upper to the contour of a last, of mechanism automatically operative in time relation to said conforming means to apply a binder round the end of the shoe exteriorly of the periphery of the shoe bottom and to fasten the binder to the shoe.

48. In a machine of the class described, the combination with shoe positioning means, of end embracing wipers mounted for movement toward and from the shoe, mechanism movable with said wipers for supporting a binder and for applying it round the end of the shoe exteriorly of the periphery of the shoe bottom, and additional mechanism for fastening the binder to the shoe.

49. In a machine of the class described, the combination with means for conforming an upper to the contour of a last, of means for supporting and applying round the end of the shoe exteriorly of the periphery of the shoe bottom a binder having parts adapted to overlie the shoe materials on the bottom of the last, and mechanism automatically operative in time relation to said binder applying means to fasten said parts of the binder to the shoe.

50. In a machine of the class described, the combination with shoe positioning means, of end embracing wipers mounted for movement lengthwise of the shoe, mechanism movable with said wipers for applying a binder round the end of the shoe exteriorly of the periphery of the shoe bottom, members movable laterally of the shoe for engaging portions of said binder and bending them inwardly over the shoe bottom, and mechanism for driving fasteners to secure said inwardly bent portions of the binder to the shoe.

51. A machine of the class described having, in combination, means for pulling an upper over a last, end embracing wipers mounted for movement lengthwise of the

shoe, means for applying a binder round the end of the shoe exteriorly of the periphery of the shoe bottom, and side wipers and tackers movable laterally of the shoe and arranged to bend portions of the binder inwardly over the shoe bottom and to drive tacks through said inwardly bent portions to secure the binder to the shoe.

52. In a machine of the class described, the combination with shoe positioning means, of end embracing wipers and supporting means for moving them inwardly over the bottom of the shoe, and additional means automatically operative substantially throughout the inward movement of said wipers over the shoe to move them transversely of the plane of the shoe bottom for applying increasing pressure to the margin of the upper.
53. In a machine of the class described, the combination with shoe positioning means, of end embracing wipers, wiper supporting means movable to carry said wipers

inwardly over the bottom of the shoe, and mechanism automatically operative in response to the inward movement of the wipers to effect relative movement of the shoe and the wipers in a direction transverse to the plane of the shoe bottom to increase the pressure of the wipers on the upper. 25 30 35

54. In a machine of the class described, the combination with shoe positioning means, of end embracing wipers, a wiper support movable to carry said wipers inwardly over the bottom of the shoe, a device for effecting relative movement of said wiper support and the shoe in a direction transverse to the plane of the shoe bottom to increase the pressure of the wipers on the upper, and connections between said device and the wiper support for operating the device by the movement of said support. 40

In testimony whereof I have signed my name to this specification.

CHARLES F. PYM.
